UNITED STATES PATENT OFFICE.

FRED D. HOLDSWORTH, OF CLAREMONT, NEW HAMPSHIRE, ASSIGNOR TO SULLIVAN MACHINERY COMPANY, A CORPORATION OF MASSACHUSETTS.

CONTROLLING MECHANISM.

Application filed May 28, 1924. Serial No. 716,508.

My invention relates to controlling mechanisms.

An object of my invention is to provide an improved controlling mechanism. Another object of my invention is to provide an improved controlling mechanism for a compressor of the gasoline engine driven type. A further object of my invention is to provide an improved controlling mechanism for a compressor whereby the power supply to the compressor driving engine is controlled in an improved manner. A still further object of my invention is to provide an improved controlling mechanism for a gasoline engine driven compressor having improved automatic and manual speed regulating mechanism. These and other objects will however hereinafter more fully appear.

In the accompanying drawings I have shown for purposes of illustration one embodiment which my invention may assume in practice.

In these drawings,—

Fig. 1 is a side elevation of a compressor mechanism equipped with the improved controlling mechanism.

Fig. 2 is an enlarged side elevation of the improved controlling mechanism per se.

Fig. 3 is a central longitudinal horizontal sectional view partially in plan taken substantially on line 3—3 of Fig. 2.

Fig. 4 is a transverse vertical section taken substantially on line 4—4 of Fig. 3.

In this illustrative form of my invention I have shown a portable compressor mechanism of the truck supported type mounted on a wheeled truck 1 including a vertical compressor 2 driven by a gasoline engine 3 and discharging into a receiver 4 through pipe connections 5, the compressor herein being supplied with usual suction inlet valves 6 which are adapted to be held open at certain times by plungers, not shown, to unload the compressor in a well known manner. It will be observed that the motor 3 is provided with a constant speed governor, generally designated 7, of the well known centrifugal weight type, herein operatively connected to a drive shaft 8 suitably driven by the motor through connections 9 which may be of any desired form adapted, upon a speed above or below a predetermined point, to move forward or retract a plunger 10, shown in Fig. 3, to swing an eccentric pin 11 around a shaft or pivot 12 to which a usual normal-

ly open ported throttle valve 13 is secured. This valve 13 is disposed in the gaseous mixture supply conduit 14 leading to the motor cylinders; and accordingly by moving the ported valve to open or closed position, the speed of the motor may be increased or decreased to the desired speed.

It will herein be noted that cooperating with the centrifugal governor operated controlling mechanism is controlling mechanism of improved form which is responsive to the variation of pressure within receiver 4 and which also operates the throttle valve 13. This mechanism, generally designated 15, is adapted to be operated by receiver pressure supplied through a usual pilot valve 16 of the well known Judson type which is adapted to open at a predetermined pressure to supply the pressure through a pipe connection 17 and a pipe connection 18 leading to the usual plungers acting on the suction inlet valves to hold the same off their seats, unloading the compressor. At the same time pressure passes through a branched pipe connection 19 which communicates with a stepped cylindrical chamber or bore 20 to propel a piston 21 longitudinally of the cylinder, the piston herein being provided with a suitable packing washer. It will be observed that this chamber 20 is formed in a casing or housing 22 suitably supported as by bolts to a member 22' disposed between the casing 23 of the constant speed governor 7 and a member 24 in which the eccentric pin 11 and its cooperating parts are housed, the member 24 herein being formed integral with the conduit 14. It will also be noted that the casing 22' is herein held in rigid non-rotative relation with the member 24 as by a key 24'. The piston 21 is also adapted to be held in its inoperative position by counter-pressure springs 25 suitably connected at 26 to portions formed on the casing 22 and to a crosshead 27 suitably formed on the piston 21. Within the casing 22 is mounted a lever 28 pivoted intermediate its ends on a pin 29 eccentrically located in a cylindrical plug 30 carried within a bore 30' formed in the casing 22'.

One end of this lever 28 projects into a hollowed out portion 31 formed in the piston 21 and is provided with a bifurcated portion pivoted at 32 to a plunger 33. Cooperating with this plunger is a coiled centripetal governor spring 34 carried by a

member 35 and held in adjusted position by a follower 36. The opposite end of this lever is suitably connected at 37 to the centrifugal governor plunger 10 which controls the position of the throttle valve 13. Suitably secured to the plug 30 is a projecting lever 38 by which the plug 30 may be rotated to cause the eccentric pin 29 to assume different positions and thereby vary the compression of the governor spring disposed in the air piston or plunger 21 and thus vary the position of the centrifugal weights within the governor 7 and consequently the flow of gaseous mixture to, and consequently the speed of, the gasoline operated driving engine. This lever 38 is herein adapted to be held in its different adjusted positions by means of a serrated portion formed on a quadrant member 40 suitably secured as 20 by bolts 41 to the casing 22'. An adjustable stop member 42 is also suitably threaded as at 43 within a boss formed on the casing 22 and this stop prevents excessive movement of the piston 21. It will thus be noted that as the piston 21 is propelled longitudinally within the chamber 20, the lever 28 is swung about its pivot 29, moving the plunger 10 of the constant speed governor 7 to the right (see Fig. 3) and causing the pin 11 to be swung about its pivot 12 to close the throttle valve 13 and decrease the supply of gaseous mixture to the engine and consequently the speed thereof.

The operation of my improved controlling mechanism will be readily apparent from the description given, but to summarize, it will herein be noted that when the pressure within the receiver 4 reaches a predetermined pressure, the pilot valve 16 will 35 open, simultaneously admitting pressure to the plungers acting on the inlet valves to open the latter, and to the pipe 19 leading to the cylinder 20, to move the piston 21 longitudinally and thereby swing the lever 40 28 about its pivot and move the plunger 10 to swing the valve 13 closed and decrease the speed of the engine. When, however, the pressure in the receiver drops below a predetermined point, the pilot valve 16 closes 45 and exhausts the pressure behind the inlet valve unseating plungers and the governor piston 21 and causes both the compressor to be loaded and the speed of the engine to be increased. If it is desired to manually 50 adjust the speed of the engine, the lever 38 may be swung in either direction, thereby varying the position of the eccentric pivot pin 29 and consequently the compression of the governor spring 34. The governor 7 of 55 course provides means for maintaining the speed of the engine 3 constant.

While I have in this application specifically described one embodiment which my invention may assume in practice, it will be 60 understood that this embodiment of the

same is shown for purposes of illustration and that the invention may be modified and embodied in various other forms without departing from its spirit or the scope of the appended claims. 70

What I claim as new and desire to secure by Letters Patent is:

1. In a compressor controlling mechanism, a compressor, a driving engine therefor having a controlling valve, speed responsive means for controlling the position of said valve, pressure responsive means for controlling the position of said valve, and manual means including an eccentric for controlling said last mentioned means. 80

2. In a compressor controlling mechanism, a compressor, a driving engine therefor having a controlling valve, speed responsive means for controlling the position of said valve, pressure responsive means for controlling the position of said valve, and manual means including an eccentric and a co-operating lever for controlling said last mentioned means. 85

3. In a compressor controlling mechanism, a compressor, a driving engine therefor having a controlling valve, speed responsive means for controlling the position of said valve, pressure responsive means for controlling the position of said valve, and manual means including a rotatable eccentric and operating lever for controlling said last mentioned means. 90

4. In a compressor controlling mechanism, a compressor, a driving engine therefor including a controlling valve, speed responsive means for controlling said valve to control said engine, and pressure responsive means including a pivoted lever cooperating with a portion of said speed responsive means, 100 and manual means for directly adjusting the position of said lever. 105

5. In a compressor controlling mechanism, a compressor, a driving engine therefor having a throttle valve, speed responsive means for controlling the position of said valve including a lever, and means for varying the fulcrum point of said lever. 110

6. In a compressor controlling mechanism, a compressor, a driving engine therefor having associated therewith adjustable means for varying the speed of said engine, speed responsive means for controlling the adjustment of said means including a lever, and means for varying the fulcrum point 115 of said lever. 120

7. In a compressor controlling mechanism, a compressor, a driving engine therefor having a throttle valve, speed responsive means for controlling the position of said valve including a spring loaded lever, and means for varying the fulcrum point of said lever to vary the spring pressure on 125 said lever.

8. In a compressor controlling mechanism, 130

- a compressor, a driving engine therefor having associated therewith adjustable means for varying the speed of said engine, speed responsive means for controlling the adjustment of said means including a spring loaded lever, and means for varying the fulcrum point of said lever to vary the spring pressure on said lever.
9. In a compressor controlling mechanism,
10. a compressor, a driving engine therefor having a throttle valve, speed responsive means for controlling the position of said valve including a spring loaded lever, and means for varying the fulcrum point of said
- lever to vary the spring pressure transmitted by said lever.
10. In a compressor controlling mechanism, a compressor, a driving engine therefor having associated therewith adjustable means for varying the speed of said engine, speed responsive means for controlling the adjustment of said means including a spring loaded lever, and means for varying the fulcrum point of said lever to vary the spring pressure transmitted by said lever.

In testimony whereof I affix my signature.

FRED D. HOLDSWORTH.
